Des. 187,922
Patented May 17, 1960

187,922

CONTROL MACHINE FOR RAILWAY CONTROL OR SIMILAR ARTICLE

Robert A. Woods, Verona, and Charles W. Haeckler,
Swissvale, Pa., assignors to Westinghouse Air Brake
Company, Wilmerding, Pa., a corporation of Pennsyl-
vania

Application December 18, 1958, Serial No. 53,820

Term of patent 14 years

(Cl. D26—13)

Fig. 1.

Fig. 2.

Fig. 3.

Fig. 1 is an elevational perspective view of a control machine for railway control or similar article embodying our new design;

Fig. 2 is a plan view of Fig. 1; and

Fig. 3 is an isometric sectional view, taken along lines 3—3 of Fig. 2.

For convenience in illustration, the representative surface controls and representative track diagram in Fig. 1 have been omitted in Figs. 2 and 3 respectively.

We claim:

The ornamental design for a control machine for railway control or similar article, as shown and described.
